UNITED STATES PATENT OFFICE.

JOHN W. DUVAL, OF LOS ANGELES, CALIFORNIA, ASSIGNOR TO AUTOMATIC SELECTOR COMPANY, OF LOS ANGELES, CALIFORNIA, A CORPORATION OF CALIFORNIA.

AUTOMATIC DISPLAY-MACHINE.

1,176,704.

Specification of Letters Patent. Patented Mar. 21, 1916.

Application filed December 26, 1913. Serial No. 808,689.

To all whom it may concern:

Be it known that I, JOHN W. DUVAL, a citizen of the United States, residing at the city of Los Angeles, in the county of Los Angeles and State of California, have invented a new and useful Improvement in Automatic Display-Machines, of which the following is a specification.

My invention relates to a machine for displaying advertisements or other desired information in which the information is printed or otherwise mounted upon a series of roller curtains, preferably of fabric, each curtain being mounted upon an individual roller, and the object thereof is to provide a machine of that class which will automatically select and expose to view the curtain containing the desired information.

Another object is to provide means for mounting maps and the like which are in constant use upon rollers whereby the operator may at will cause the desired map or the like to be exposed to view. I accomplish this object by the device described herein and illustrated in the accompanying drawings forming a part hereof, in which:

Figure 1 is a side elevation partly in section of so much of my device as is necessary to illustrate my invention—Fig. 2 is a top plan of Fig. 1; Fig. 3 is a detail of one of the curtain rollers; Fig. 4 is an end view of Fig. 3; Figs. 5, 6 and 7 are diagrammatic details of the selecting levers and their adjunct parts; Fig. 8 is a fragmentary detail of a portion of the locking bar; Figs. 9 and 10 are details of the reversing mechanism; Fig. 11 is a perspective detail of the trip levers; Fig. 12 is a perspective of my complete mechanism; Fig. 13 is a detail of the switch mechanism.

In my preferred form my device consists of a casing or cabinet 15 having one end 17 thereof provided with hinges 18, in the central portion of the front face of which is mounted a transparent panel 16, preferably of glass. Near the inner side of the back of the cabinet and near each side thereof are securely mounted vertically extending bearing plates or standards 19 and 20 which are secured at their ends to the top and bottom of the cabinet. Standard 19 has annular openings 21 extending therethrough at equally spaced intervals along a portion of its length in which are received annular bearings 22. These bearings are provided

at their inner ends with square sockets 23 in which are received one end of rollers 25, and a similar socket 26 in which a key or wrench is inserted when it is desired to tighten or loosen the tension of the roller spring. A set screw 27 provides means for retaining these bearings in their adjusted positions. Standard 20 is provided with similar openings and bearings except that the sockets in bearings 22 are round and sockets 26 are omitted. At the edges of standards 19 and 20 nearest the back of the cabinet and near the lower ends thereof are mounted bearings 28 in which is revolubly mounted a rocking shaft 30. Shaft 30 has rigidly mounted thereon a plurality of rocking levers 31, one end 32 of which is reduced in size and extends forwardly to about the vertical central line of standards 19 and 20. The other end of rocking lever 31 extends rearwardly and is pivotally secured in a cross-head 33. The other end of cross-head 33 is connected by a similar cross-head 34 to a link 35 which link is rigidly mounted on a selecting arm shaft 36 intermediate the ends thereof. Shaft 36 is revolubly mounted in bearings 37 secured upon the rear edges of standards 19 and 20 and has rigidly secured upon each end thereof one end of selecting arms 38 and 39. The other ends of these selector arms extend forwardly and downwardly at an angle to near the front edges of the standards where they terminate in hooks 40 and 41. Rollers 25 have curtains 42 mounted thereon in the usual well known manner, which curtains are provided at their free ends with curtain rods 43, the ends of which normally lie in recesses 44 in the front edges of standards 19 and 20 just above and in the path of hooks 40 and 41 of selector arms 38 and 39.

On the front edges of standards 19 and 20 and parallel with shaft 30 is rigidly mounted a shaft 45 on which are loosely mounted a plurality of trip levers 46, one end 46^a of each of which normally extends rearwardly and downwardly at an angle to a point just under the end 32 of rocking lever 31. The other end of each trip lever 46 normally extends upwardly and forwardly and terminates at a point just outside the path of operating bar 47, which bar is slidably mounted in bearings 48 secured to the front edges of the standards and slides vertically. One side of end 46^a of trip lever

- 46 has an outwardly extending ear or lug 50 which normally lies in contact with one edge of an operating link 51 (Fig. 11). Link 51 is loosely mounted on shaft 45 at 5 the side of lever 46 and has its free end pivotally connected with the inner end of key rod 52. The other end of key rod 52 is secured within the inner end of key bar 53, which key bar terminates in a finger piece 10 54 outside of the cabinet. A locking lever 55 is pivotally mounted at the bottom of the casing and extends upwardly therefrom and terminates in a hook 56 and is adapted when bar 47 is depressed to hook over said bar and 15 retain it in its depressed position. Locking lever 55 has a forwardly extending arm 57 intermediate the ends thereof which provides means for releasing bar 47 as hereaftter explained.
- 20 Operating shafts 58 and 59 are mounted in bearings near the top and bottom respectively of casing 10 between the front of said casing and standards 19 and 20, and have rigidly mounted thereon near each end 25 sprocket wheels 60 and 61 around which travel sprocket chains 62 and 63. Chains 62 and 63 are provided with selector hooks 64 the use of which will be hereafter explained.
- 30 A motor 66 is mounted on suitable mountings within cabinet 15 and drives a jack shaft 67 by means of bevel gears 68 and 69. A friction pinion 70 is rigidly secured upon the lower end of shaft 67. A hub 71 having 35 friction disks 72 and 73 secured at the ends thereof is slidably and non-revolubly mounted on shaft 59, so that one of the friction disks will be at each side of pinion 70, which disks are adapted to be brought into contact with pinion 70 to drive shaft 59 in the 40 desired direction.
- Hub 71 is provided with an annular groove 74 intermediate the ends thereof in which is received an annular collar 75. Collar 75 is 45 provided with outwardly extending studs 76 which are received in the free ends of an operating yoke 77. The other end of yoke 77 is rigidly mounted on shaft 78 mounted in suitable bearings, and is provided with L-shaped operating arms 79 and 80 extending 50 at right angles thereto. Arm 79 extends rearwardly from shaft 78 and terminates at a point just below and in the descending path of bar 47. Arm 80 extends forwardly 55 from shaft 78 and terminates at a point in the descending path of lug 81 on locking bar 82. Locking bar 82 is of substantially U-shape with the legs thereof near each end of the cabinet and is slidably mounted on the 60 inner side of the front of the cabinet by screws or other suitable means to slide vertically.
- The motor 66 is operated by means of a switch 83 mounted upon one side of the casing 65 one post 84 of which is connected to the motor and the other post 85 is connected to a supply wire in the usual well known way. Switch 83 has one end pivotally connected to post 84 and then extends forwardly to near the front of the cabinet and terminates 70 in a downwardly disposed hook 86. A coil spring 87 has one end connected to the free end of switch 83 and the other end secured to the side of the cabinet and is adapted to normally hold said switch from engagement 75 with post 85. A retaining hook 88 is pivotally mounted on the inner side of casing 15, the upper hooked end of which is adapted to engage the hooked end 86 of switch 83 and holds the same in operative engagement with post 85 against the power of spring 87 when the device is in operation. Hook 88 is provided with a releasing member 88a extending rearwardly therefrom near its pivot for a purpose hereafter described. An operating rod 89 has a slot 90 in the upper end thereof through which passes a stud or pin 91 secured near the end of switch 83, and said stud extends downwardly therefrom and the lower end thereof is pivotally connected to the free end of a link member 92. The other end of link 92 is rigidly mounted upon one end of shaft 93. Shaft 93 extends from side to side of the cabinet and is revolubly mounted in bearings secured to the 95 sides thereof. Switch operating members 94 are rigidly mounted on shaft 93 just above key rods 52, there being one operating member for each key rod. These operating members extend downwardly from shaft 93 to a 100 point just above the key rods so that when the key rods are pressed inwardly the collars 52a on said key rods will move the lower ends of said operating members inwardly and rock shaft 93.
- In the operation of my device it will be understood that there will always be one curtain unrolled and exposed to view. When the key is pressed shaft 93 will be rocked as 105 before described. This causes link 92 to pull rod 89 downwardly and by means of pin 91 draws switch 83 into contact with post 85 and completes the circuit and starts the motor. When switch 83 is drawn down hook 88 will then engage the hooked end 86 of switch 83 and hold the same in its operative position. At the same time link 51 is given 110 a partial rotation which carries trip lever 46 into the position shown in Fig. 6 and is locked in that position by locking bar 82 which is received in a slot in the lower side of the key bar. As the motor starts it will rotate the operating shaft and sprockets to 115 the left. This causes the selector hooks 64 on their respective chains to travel upwardly and then over sprockets 61 and then downwardly and allows curtain 42 to be rolled upon its roller in the usual well known manner. Further downward travel of the 120 selector hooks will cause them to strike and 125

depress operating bar 47 which bar will operate the friction clutch mechanism and reverse the direction of rotation of the operating shaft 59. Bar 47 will also strike and depress the end of trip lever 46 to the position shown in Fig. 7. These movements will cause the end 46^a of said lever to strike and elevate the end 32 of rocking lever 31 which last movement will cause said lever 31 to rock on its shaft and through cross heads 33 and 34 and their connecting rod will rock shaft 36 and will elevate the outer end of selector arms 38 and 39 and will draw the curtain rod 43 into the upward path of selector hooks 64. Hooks 64 will on their upward travel engage rod 43 and carry the same up over roller 58^a mounted on the upper shaft 58 and then downwardly adjacent the inner face of the transparent panel 16. Chain 63 has one of the pivot pins which connect the links extending outwardly from the side thereof. This pin is near to and in advance of the selector hooks and is adapted to strike member 88^a of hook 88 and withdraws hook 88 from engagement with the hooked end 86 of switch 83. Spring 87 will then act to withdraw switch 83 from contact with post 85 and breaks the circuit of the motor. At the time the motor circuit is broken hooks 64 are in close proximity to locking bar 82 and the momentum of the motor and the other moving parts causes the further travel of said hooks to depress bar 82 and release it from the slot in the key rod. The key rod and connected parts are then returned to normal positions. The depression of bar 82 causes it to engage arm 80 of yoke 77 and shift said yoke to change the direction of rotation of shaft 59 when the machine is again operated.

Having described my invention what I claim is:

1. In an advertising machine a cabinet having an opening in the front wall thereof; a transparent panel in said opening; rollers journaled in said cabinet intermediate the panel and the rear wall of the cabinet; curtains mounted on said rollers adapted to have printed thereon advertising matter; traveling means adapted to move any one of said curtains into view through said panel; a motive device for said traveling means; selector means operated by said traveling means to select any desired curtain and cause the same to be engaged by said traveling means; and an independent manually controlled device constructed and arranged to set said motive device in motion and to position the selector means for engagement with the traveling means.

2. An advertising device comprising a cabinet; spring retracted rollers mounted in stationary bearings in said cabinet; curtains wound around said rollers; traveling means adapted to engage the free end of any one of said curtains and unwind the same; a

motive device for said traveling means; selector means operated by the traveling means and adapted to cause the free end of any one of said curtains to engage the unwinding means; a manually controlled device for each of said rollers adapted to set said motive device in operation and to move the selector means into position for engagement with the traveling means upon the operation of the controlling means; and means to arrest the operation of said motive device when a curtain is fully displayed.

3. An advertising device comprising a cabinet; rollers journaled in stationary bearings in said cabinet; curtains wound upon said rollers; traveling means adapted to engage the free ends of said curtains and unwind the same; selector means operated by the unwinding means adapted to move the free ends of said curtains into engagement with the unwinding means; manually controlled devices adapted to set in motion said traveling means and to position the selector means for engagement therewith; and means operated by the traveling means to arrest the movement of said traveling means when a curtain is fully displayed.

4. In a display machine a cabinet having an opening in the front wall thereof; a transparent panel in said opening; spring rollers journaled in stationary bearings in said cabinet; curtains wound upon said rollers adapted to have printed thereon advertising matter; a rod secured to the free end of each of said curtains; operating shafts journaled in said cabinet above and below said rollers; a motive device for said operating shafts adapted to rotate said shafts; sprocket wheels mounted on said shafts; sprocket chains connecting said sprocket wheels; selector hooks mounted on said chains adapted to engage the rods in the free ends of the curtains and unroll the same; selector arms pivotally mounted in said cabinet adapted to move the free ends of the curtains into the path of the selector hooks; means operated by the selector hooks adapted to operate said selector arms; and means operated by said sprocket chain to stop the motive device when a curtain is fully displayed.

5. An advertising device comprising a casing having an opening in the front thereof; a plurality of spring retracted rollers journaled in stationary bearings in said casing; curtains winding on said rollers; traveling means adapted to operate in one direction to unwind said curtains and in a reverse direction to rewind the same; a motive device for said traveling means; selector mechanism operated by said traveling means adapted to move the free ends of said curtains into position for engagement with said traveling means; an independent manually controlled device for each of said

rollers adapted to set in motion said motive device upon the operation of said controlling means; means operated by said manually controlled device adapted to move said selector mechanism into position for engagement with the traveling means; means operated by said traveling means to cause the same to travel in a reverse direction; means operated by the traveling means to 10 restore the manually controlled devices to normal position; and means operated by the traveling means to arrest the movement of the motive device.

6. An advertising device comprising a casing having an opening in the front thereof; a plurality of rollers journaled in said casing; curtains winding on said rollers; traveling means adapted to operate in one direction to unwind said curtains and in a 15 reverse direction to rewind the same; a motive device for said traveling means; means operated by said traveling means to cause the same to travel first in one and then in a reverse direction; selector mechanism 20 operated by said traveling means adapted to move the free ends of said curtains into position for engagement with said traveling means; a series of independent manually controlled devices adapted to set in motion 25 said motive device upon the operation of the controlling means and to move the selector mechanism into position to be engaged by the traveling means; means to lock 30 said manually controlled devices in their operative position; and means operated by the traveling means to arrest the movement of said motive device when a curtain is 35 fully displayed.

7. In a display machine a cabinet having an opening in the front wall thereof; a transparent panel in said opening; a plurality of rollers mounted in stationary bearings in said cabinet; a curtain wound on each of said rollers; manually controlled 40 means to cause any one of said curtains to be selected for display; traveling means set in motion by said selector means to unwind said selected curtain and expose the same through said panel; and means operated by 45 said traveling means to arrest the same when a curtain is fully displayed.

8. A mechanical directory comprising a casing having an opening in the front wall thereof; a plurality of rollers journaled therein; curtains secured at one end to said rollers and wound thereon, there being one curtain for each roller, said curtains having their free ends adapted to be moved into engagement with an unwinding means; unwinding means for said curtains comprising intermittently moving belts one at each end of said rollers; selector hooks secured to said belts adapted to engage the free ends of said curtains; means to move said belts 60 first in one and then in a reverse direction;

manually controlled means to select any one of said curtains for display; means operated by said selector means to set in motion the unwinding means upon the operation of the controlling means; and means operated by 70 the unwinding means to cause the selector means to move the free end of the selected curtain into the path of movement of said selector hooks whereby said hooks engage the free end and unroll the curtain; and 75 means to arrest the movement of said unwinding means when a curtain is fully displayed.

9. In a display machine a plurality of rollers revolvably mounted in stationary 80 bearings; curtains wound around said rollers; means to actuate any desired curtain; manually operated means to select any one of said curtains for display; means operated by said selector means to start in motion the 85 curtain actuating means; means operated by the curtain actuating means to move the free end of said selected curtain into engagement with said actuating means; and means to stop the curtain actuating means 90 when a curtain is fully displayed.

10. A mechanical directory comprising a casing having an opening in the front wall thereof; a transparent panel in said opening; a plurality of rollers journaled in said casing; a curtain wound around each of said rollers; a rod in the free end of each of said curtains; a motive device adapted to operate in one direction to unwind said curtains and in a reverse direction to rewind the same; selector mechanism operated by said motive device in its rewinding movement to move the free end of the selected curtain into a position to be engaged by said motive device on its return movement; an independent manually controlled device for each of said curtains adapted to set the motive device in operation to rewind the curtains upon the operation of the controlling means; means operated by said controlling 105 means adapted to move said selector mechanism into position for engagement with the motive device; means to lock said manually controlled device in its operative position; means operated by said motive device in its rewinding movement to cause the same 110 to travel in a reverse direction; means operated by said motive device in its reverse movement to arrest the movement thereof; and means operated by the motive device to 115 release said manually controlled device.

11. A mechanical directory comprising a casing having an opening in the front thereof; a plurality of rollers journaled in said casing; a curtain winding on each of said rollers; a rod in the free end of each of said curtains; actuating means for said curtains; a motive device for said actuating means; transmission mechanism connecting said motive device and actuating means adapted to 120 125 130

cause said actuating means to travel first in one and then in a reverse direction; selector mechanism for each of said rollers operated by said actuating means adapted 5 to move the free end of said selected curtain into engagement with said actuating means; an independent manually controlled device constructed and arranged to set said motive device in operation upon the operation of 10 the controlling means and to position the selector mechanism in position to be operated by the actuating means; means operated by said curtain actuating means to operate said transmission mechanism; and 15 means operated by said actuating means to arrest the movement of said motive device when a curtain is fully displayed.

12. A mechanical directory comprising a casing; a plurality of rollers journaled 20 therein; a curtain winding on each of said rollers; a rod in the free end of each of said curtains; traveling means adapted to operate in one direction to unwind said curtains and in a reverse direction to rewind the 25 same; a motive device for said traveling means; selector mechanism operated by said traveling means adapted to move the free end of said curtains into position for engagement with said traveling means; a 30 manually operated device for each of said rollers adapted to set in motion said motive device and to move the selector mechanism into position for engagement with the traveling means; means to lock said selector 35 mechanism in its operative position; means to lock said manually operated device in its operated position; means operated by the traveling means adapted to cause the same to travel in a reverse direction; means op- 40 erated by said traveling means in its reverse direction adapted to release the selector mechanism and to restore the same to normal position; means operated by said traveling means to release said manually op- 45 erated device; and means operated by said traveling means to stop the movement of

said motive device when a curtain is fully displayed.

13. A mechanical directory comprising a casing; a plurality of rollers journaled 50 therein; a curtain winding on each of said rollers; traveling means adapted to operate in one direction to unwind said curtains and in a reverse direction to rewind the same; a motive device for said traveling means; se- 55 lector mechanism adapted to be operated by said traveling means in its unwinding movement to move the free end of any desired curtain into position for engagement with the traveling means; means to lock said se- 60 lector mechanism in its operated position; an independent manually controlled device for each of said rollers adapted to set in motion said motive device to rewind said curtains and to move the selector mechanism 65 into position to be operated by the traveling means; means to lock said manually controlled device in its operated position; means operated by said traveling means in its re- 70 winding movement to cause the same to travel in a reverse direction to unwind said curtains; means operated by said traveling means in its unwinding movement to re- 75 lease the selector mechanism; means operated by said traveling means in its unwinding movement adapted to release said manually controlled device; means operated by the traveling means in its unwinding movement to arrest the movement of said motive device; and means operated by said travel- 80 ing means in its unwinding movement to cause said traveling means to travel in a re- 85 verse direction upon the operation of said manually controlled device.

In witness that I claim the foregoing I have hereunto subscribed my name this 25th day of November, 1913.

JOHN W. DUVAL.
